(57) **CLAIM**

The ornamental design for tire, as shown and described.

DESCRIPTION

FIG. 1 is a perspective view of tire showing our new design;

FIG. 2 is a front elevation view thereof;

FIG. 3 is a back elevation view thereof;

FIG. 4 is a left side view thereof;

FIG. 5 is a right side view thereof;

FIG. 6 is a top plan view thereof;

FIG. 7 is a bottom plan view thereof;

FIG. 8 is a partially enlarged view of FIG. 2; and,

FIG. 9 is a partially enlarged view of FIG. 4.

The broken lines shown on the drawings depict portions of the tire that form no part of the claimed design.
